UNITED STATES PATENT OFFICE

HAROLD LOUIS MATTHES, OF MONROE, MICHIGAN, ASSIGNOR TO THE WEIS MANUFACTURING COMPANY, OF MONROE, MICHIGAN, A CORPORATION OF MICHIGAN

VISIBLE INDEX SYSTEM

Application filed May 18, 1927. Serial No. 192,171.

This invention relates to card holders for visible index systems, such as those in which the cards are held in overlapping relation on trays or slides, which latter are usually insertible in and removable from a cabinet.

Generally stated, the object of the invention is to provide a form of card holder of simple, inexpensive form, which can be easily placed in the tray or slide, and easily removed therefrom, and to provide means on the ends of said card holders to space them apart, in the form of rollers on the opposite ends of each card holder, whereby the card holders are not only spaced apart in a manner to make it easy to swing the cards back and forth, but whereby it is also easy to slide or move the card holders back and forth in the guides in which said rollers travel, said rollers rotating easily to permit shifting of the holders toward and away from each other, and at the same time providing trunnion bearings in which the opposite ends of the card holders are mounted to swivel easily when it is necessary to swing the cards toward and away from each other.

It is also an object to provide a novel and improved form of sheet-metal card holder having gripping jaws for bending or crimping the card, whereby the latter will more securely be held in place.

It is also an object to provide certain details and features of construction tending to increase the general efficiency and the desirability of card holders of this particular character.

To these and other useful ends, the invention consists in the matters hereinafter set forth and claimed, and shown in the accompanying drawings, in which—

Fig. 1 is a plan view of a tray or slide provided with card holders embodying the principles of the invention.

Fig. 2 is a transverse section on line 2—2 in Fig. 1.

Fig. 3 is a perspective of a portion of a card holder and card, showing the formation of the card holder before the roller is applied thereto.

Fig. 4 is an enlarged detail sectional view showing the formation of the end portion

of the card holder after the roller is applied thereto.

Fig. 5 is an enlarged cross-section of one of the sheet-metal card holders, showing the formation of the jaws thereof for bending or crimping the card, as will hereinafter more fully appear.

As thus illustrated, the invention comprises a sheet-metal tray 1 having parallel guides 2 in the opposite side edge portions thereof, as shown.

Each sheet-metal card holder has a straight middle portion 3 comprising parallel portions for resiliently gripping and holding a card 4 of any suitable character. The opposite ends of the sheet-metal card holder are provided with rollers 5 rotatably held in place thereon by the expanded or spread end portions 6 of the sheet-metal card holder. Thus each sheet-metal card holder has a slot 7 into which the card can be forced, and the springy, resilient jaws of the card holder will grip the card and hold it in position, so that the card can only be removed by forcibly pulling it out from the slot in the card holder. The rollers 5 engage each other, when the holders and cards are properly assembled, thus spacing the card holders apart a sufficient distance to permit each card holder to swivel or partially rotate in its rollers 5, the latter thereby serving as trunnion bearings for each card holder. When the card holders are moved bodily, or moved toward and away from each other, the rollers 5 rotate in the guides, and travel easily along these guides, making it easy to shift the cards and card holders.

One method of assembly, as shown in Fig. 3, is to leave the end portions 7 of each sheet-metal card holder straight, as shown, and to insert these straight portions into the rollers 5, and to then expand the end portions of the holder to form the funnel-shaped portions 6, which prevent displacement of the rollers. Each card holder is preferably provided with the shoulders 8 at the ends of the jaws of the card holder, and alignment of the cards is obtained by bringing the side edges of the cards opposite these shoulders 8 in the manner shown.

Any suitable or desired means can be employed for holding the card holders in position, against shifting around, such as the ordinary and well known flexible, springy, metal strip 9 for the inner end portion of the tray, having end portions that will frictionally engage in the guides 2 previously mentioned, the strip being bowed upward to enable its end portions to enter said guides, and its straightening-out action then serving automatically to hold it in position in said guides. This is an old expedient, and does not need further description, as it forms no part of the invention. At the other side the card holders can be held in position by projections 10 extending into the grooves of the guides, from any suitable portion of the structure, and the tray or slide can be of any suitable or desired length, it will be understood, to accommodate as many card holders as may conveniently be held in one tray or slide.

With this arrangement, the card holders are spaced apart in a manner permitting them to oscillate or rotate freely in their rollers, the latter serving as trunnion bearings for this purpose, and hence the cards can be moved toward and away from each other with the utmost freedom, and without friction between the card holders. The rollers provide spacing means that are uniform, and which can rotate and yet at the same time always have the same spacing diameter, so that regardless of rotation of these rollers, the card holders are always spaced the same distance apart.

The rollers 5, of course, prevent removal of the cards by motion thereof longitudinally of the card holders, thus compelling insertion of the cards by edgewise movement thereof in a direction at right angles to the card holder, and compelling removal of the cards by a similar motion, inasmuch as the rollers form a stop at each end of the card holder to prevent lateral shifting of the cards to any great extent.

As shown in Fig. 5, the sheet-metal card holder 3 is preferably formed with parallel jaws, or substantially parallel jaw portions, 11 and 12, and the jaw 11 has an inturned or inwardly folded portion 13 which extends toward the resilient portion 14 by which the two jaws are flexibly connected together. The other jaw 12 has a similar inside portion 15, but this portion 15 is shorter, so that it extends a less distance toward the portion 14 as shown. The edge of portion 13 clamps the card against the inner side of outer jaw 12, while the edge of portion 15 clamps it against the face of portion 13. In this way, the card 4 when inserted is bent or crimped in the manner shown, by the edges of the portions 13 and 15, thereby securely holding the card in place, but permitting the card to be forcibly pulled out. This also provides the jaws with smooth and rounded outer edges between which the

card can easily be inserted, so that the longitudinal edges of each card holder are all smooth and rounded, and whereby each sheet-metal card holder is also made somewhat stiffer and more rigid. It will be seen that the portions 13 and 15 extend at angles to bend or buckle the card 4 in the manner shown, so that the holder in this way has a good grip on the card, as the inner edges of the portions 13 and 15 bear against the surface of the card, and thus securely anchor the latter in position.

What I claim as my invention is:—

1. In combination, a tray or slide having parallel inner guides at the opposite sides thereof, cylindrical rollers disposed in position to travel in said guides, each roller being free to rotate in one of said guides, card holders having trunnions swiveled in said rollers, so that said rollers are free to rotate on the end portions of the card holders and act as trunnion bearings for said card holders, the cylindrical bearings engaging each other in each guide and spacing the card holders apart to prevent friction and interference between the card holders, and cards detachably held in said holders.

2. A structure as specified in claim 1, each card holder comprising resilient sheet-metal gripping jaws for frictionally gripping a card, and having end portions formed to prevent removal of the rollers therefrom.

3. A structure as specified in claim 1, each card holder having expanded end portions preventing removal of the rollers therefrom.

4. A structure as specified in claim 1, said rollers preventing removal of the cards sideways or longitudinally of the card holder, and compelling edgewise insertion of the cards by movement in a direction at right angles to the length of the card holder, and compelling removal of the cards by a similar relative motion.

5. A structure as specified in claim 1, each roller having a beveled seat in its outer end, and each card holder having its end portions flared to engage said beveled seats.

6. A structure as specified in claim 1, each card holder being made of sheet-metal having jaws resiliently connected together to clamp a card between them, said jaws being each provided with an inturned portion of sheet-metal providing gripping edges spaced a distance apart transversely of the holder, and providing the jaws with outer rounded edges, said inside edges engaging the opposite surfaces of the card to hold the card in place.

7. A plurality of card holders, and means for supporting the card holders, each card holder being made of sheet-metal having jaws resiliently connected together to clamp a card between them, said jaws being each provided with an inturned portion of sheet-metal providing gripping edges spaced a distance apart transversely of the holder, and providing the jaws with outer rounded edges, said

inside edges engaging the opposite surfaces of the card to hold the card in place.

8. A structure as specified in claim 7, said rounded edges stopping short of the opposite ends of the card holder, forming shoulders by which to position the cards of the different holders in alignment at their side edges.

Specification signed this 11th day of May, 1927.
